NILS H. ANDERSON, OF MIDDLETOWN, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

KEY FOR TYPE-WRITING MACHINES.

1,160,560.

Specification of Letters Patent. Patented Nov. 16, 1915.

Application filed March 5, 1910. Serial No. 547,385.

To all whom it may concern:

Be it known that I, NILS H. ANDERSON, a citizen of the United States, residing at Middletown, in the county of Middlesex and State of Connecticut, have invented certain new and useful Improvements in Keys for Type-Writing Machines, of which the following is a full, clear, and exact description, such as will enable others skilled in the art to which it appertains to make and use the same.

This invention relates to typewriting machines, and with regard to the more specific features thereof, to the character or finger keys.

One of the objects of the present invention is to provide a simple and practical device of the above character that will be cheap to manufacture.

Another object is to provide a device of the above nature that will be efficient in operation and not likely to get out of order or become detached from the key lever in use.

A further object is to provide a device in which the character card may be rotated or straightened with relation to the other letter keys after the parts are assembled.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown various possible embodiments of this invention,—Figure 1 shows the various parts of the device separated, in order that their relation may be clearly understood; Fig. 2 is a sectional view, showing the parts assembled; Fig. 3 is a detail plan view of the cup; Fig. 4 is a sectional view on the line $x-x$ of Fig. 3; Fig. 5 is a detail view, showing the manner of securing the cup to the key lever; and Fig. 6 is a perspective view of the cup.

Similar reference characters refer to similar parts throughout the different views of the drawing.

Referring now to this drawing in detail,

1 denotes a key lever having at its forward end laterally projecting shoulders 2 and upwardly projecting lugs 3 with a cut-away portion 4 between them. A key-cup 5 is provided with recesses 6 shaped to receive and closely fit the upwardly extending lugs 3 when the parts are assembled, the underside of the cup resting on the outwardly extending shoulders 2, thereby giving the same a firm support and preventing a backward and forward tilting of the cup.

After the cup has been placed in firm position upon the end of the key lever, the upwardly projecting lugs 3 are struck or cut as by means of a sharp-pointed instrument, so as to bend or swage the sides thereof outward over the upper surface of the bottom 70 of the cup, as clearly shown in Fig. 5, whereby the cup is securely riveted to the key lever. This key cup is preferably stamped out of sheet brass by a single operation, and braces 7 are punched downwardly 75 from the underside of the cup adapted to bear against the sides of the key lever, when the parts are assembled, to prevent any lateral movement of the cup in use. These braces, interposed between the bottom of 80 the cup and the sides of the key lever, are preferably curved transversely as well as longitudinally, as shown in Fig. 6, thereby providing a very strong and compact construction. The curving of these braces also 85 provides a relatively large opening, permitting the insertion of a sharp-pointed instrument diagonally beneath the cup to engage the pad to which the letter card is secured, so that the same may be rotated relatively 90 to the cup or straightened after the parts are assembled, or at a later time, should the card become displaced by usage, thus improving the workmanlike appearance and general efficiency of the machine.

A pad 8 is placed in the bottom of the cup, to which may be permanently secured a letter card 9, above which is placed a piece of celluloid, glass or other transparent material 10, so that the character may be clearly seen, and all these parts are securely held in position by means of a cap 11, having a downwardly turned inner flange 12, adapted to fit around the cup and wedge firmly thereon, as clearly shown in Fig. 2.

It is thus seen that this invention provides

- for a simple and practical device having a small number of parts, which will be cheap to manufacture and easy to assemble and attaining, among others, the objects and 5 possessing the advantages above set forth.
- As many changes could be made in the above construction and many apparently widely different embodiments of this invention could be made without departing from 10 the scope thereof, it is intended that all matter contained in the above description or shown in the accompanying drawing shall be interpreted as illustrative and not in a limiting sense.
- 15 Having described my invention, what I claim as new and desire to secure by Letters Patent is:
1. In a device of the character described, in combination, a key-cup, a card within 20 said cup, and means for retaining said card within the cup, said cup having an opening therein whereby the card may be engaged by a suitable instrument and rotated into proper position after the parts are assembled.
  - 25 2. In a device of the character described, in combination, a key-lever, a sheet metal cup adapted to be permanently secured thereto, a character card within said cup, and removable means normally holding said card 30 against removal, said cup having an opening therein permitting the adjustment of said card into proper position after the parts are assembled.
  3. In a device of the character described, 35 in combination, a key lever, a cup mounted on said key lever, a letter card within said cup, and means for retaining said card in place, said cup having a hole therein through which an instrument may be inserted, whereby 40 the position of said card may be adjusted after the parts are assembled.
  4. In a device of the character described, in combination, a key lever, a cup rigidly secured to said key lever, a card within said 45 cup, and means for retaining said card in place, said cup having a hole on the underside thereof whereby an instrument may be inserted to rotate said card into proper position after the parts are assembled.
  5. In a device of the character described, 50 in combination, a key lever having shoulders, an integral sheet metal cup having its outer under surface resting on said shoulders and having a part extending therebelow, a letter card within said cup, and means for holding said card in place.
  6. In a device of the character described, 55 in combination, a key lever having laterally extending shoulders and upwardly extending lugs, a cup the outer under surface of which is adapted to rest on said shoulders having an opening through which said lugs are adapted to pass, and means for preventing a tilting motion of said cup when the 60 device is actuated.
  7. In a device of the character described, in combination, a key lever, a laterally extending shoulder thereon, an upwardly extending lug, a cup having an opening in its under side through which said lug is adapted to pass, the under side of said cup resting on said shoulder, and punched-up means interposed between the side of the key lever and the under side of said cup adapted to prevent a tilting motion when the device is 70 actuated.
  8. In a device of the character described, in combination, a key lever, a laterally extending shoulder thereon, an upwardly extending lug, a cup the outer underside of 80 which is adapted to rest on said shoulder and has an opening through which said lug is adapted to pass for securing said cup to said key lever, and means for preventing a tilting motion of said cup when the device is 85 actuated.
  9. In a device of the character described, in combination, a key-lever having an upwardly projecting portion, shoulders extending fore and aft thereof, a sheet metal cup having a flat underside adapted to rest on said shoulders and having an opening through which said portion of the key-lever is adapted to pass, and means integral with the cup and projecting below the underside 95 thereof coacting with the sides of the key-lever adapted to prevent a tilting motion of the cup when the key-lever is depressed.
  10. In a device of the character described, 100 in combination, a key lever, a laterally extending shoulder thereon, an upwardly extending lug, a cup adapted to rest on said shoulder and having an opening through which said lug is adapted to pass for securing said cup to said key lever, and braces interposed between the cup and the key lever adapted to prevent a tilting motion of the cup when the device is actuated.
  11. In a device of the character described, 105 in combination, a key lever, upwardly projecting lugs thereon, a cup having recesses adapted to receive said lugs, said lugs adapted to be bent over to secure the cup to said key lever, and means interposed between the key lever and cup to prevent a tilting motion 110 of the cup when the device is actuated.
  12. In a device of the character described, 115 in combination, a key lever, laterally extending shoulders thereon, upwardly projecting lugs, a cup adapted to rest on said shoulders and having recesses adapted to receive said lugs, said lugs adapted to be bent over to secure the cup to said key lever, and means integrally connected with one of said parts adapted to prevent a tilting motion 120 of the cup when the device is actuated.
  13. In a device of the character described, 125 in combination, a key lever, laterally extending shoulders thereon, upwardly projecting lugs, a cup adapted to rest on said 130

shoulders having recesses adapted to receive said lugs, said lugs adapted to be bent over to secure the cup to said key lever, and means punched outwardly from said cup 5 adapted to engage the sides of the key lever to prevent a tilting motion thereof when actuated.

14. In a device of the character described, in combination, a key lever, upwardly projecting lugs, a cup adapted to be permanently secured to said lever by means of said lugs, a character card within said cup, means 10 for holding said card in place, and means for preventing a tilting motion of said cup 15 when the device is actuated.

15. In a device of the character described, in combination, a key lever, upwardly projecting lugs, a cup adapted to be secured to said lever by means of said lugs, a character 20 card within said cup, means for holding said card in place, and means interposed between the underside of the cup and the side of the key bar to prevent a tilting motion of the cup when the device is actuated.

25. 16. In a device of the character described, in combination, a key lever, shoulders thereon extending fore and aft of the key-lever, upwardly projecting lugs, a cup adapted to rest on said shoulders and be secured to 30 said lever by means of said lugs, said shoulders being substantially co-extensive with the under side of said cup and said lugs engaging said cup at opposite sides of its center, a character card within said cup, a 35 cap adapted to bear upon said card and hold the same in place, and means for preventing a tilting motion of said cup when the device is actuated.

17. In a device of the character described, 40 in combination, a key lever having laterally extending shoulders, upwardly projecting lugs, a cup adapted to rest on said shoulders and be secured to said lever by means of said lugs, a character card within said cup, a cap 45 adapted to bear upon said card to hold the same in place, and means interposed between the underside of the cup and the side of the key lever adapted to prevent a tilting motion of the cup when the device is actuated.

50. 18. In a device of the character described, in combination, a key lever, a cup secured to said lever, and curved means independent of the securing means interposed between the underside of said cup and the key lever 55 adapted to prevent a tilting motion of the cup when the device is actuated.

19. In a device of the character described, in combination, a key lever, a cup secured to said lever, and transversely curved means 60 independent of the securing means interposed between the underside of said cup and the key lever adapted to prevent a tilting motion of the cup when the device is actuated.

65. 20. In a device of the character described, in combination, a key lever, a cup secured

to said lever, and longitudinally curved means interposed between the underside of said cup and the key lever adapted to prevent a tilting motion of the cup when the device is actuated.

70

21. In a device of the character described, in combination, a key lever, a cup secured to said lever, and transversely and longitudinally curved means interposed between the underside of said cup and the key lever adapted to prevent a tilting motion of the cup when the device is actuated.

75

22. In a device of the character described, in combination, a key lever, a cup secured to said lever, and curved means independent of the securing means interposed between the underside of said cup and both sides of said key lever adapted to prevent a tilting motion of the cup when the device is actuated.

80

23. In a device of the character described, in combination, a key lever having upwardly projecting lugs, a cup having recesses adapted to fit around said lugs whereby the said cup is secured to said lever, a character card, means for holding said card 90 in place, and curved means interposed between the underside of the cup and the side of the key lever adapted to prevent a tilting motion of the cup when the device is actuated.

95

24. In a device of the character described, in combination, a key lever having upwardly projecting lugs, a cup having recesses adapted to fit around said lugs whereby the said cup is secured to said lever, a character card, means for holding said card in place, and curved means interposed between the underside of said cup and both sides of said key lever adapted to prevent a tilting motion of the cup when the device is actuated.

105

25. In a device of the character described, in combination, a key lever, a cup, means for securing said cup to said key lever, a character card within said cup, means projecting laterally from the cup and interposed between the sides of said key lever and the cup providing an opening in the bottom of the cup whereby said character card may be rotated.

110

26. In a device of the character described, in combination, a key lever, laterally extending shoulders thereon, upwardly projecting lugs, a cup having recesses adapted to receive said lugs whereby said cup is secured to said key lever, a character card within said cup, braces punched out from the underside of said cup engaging the opposite sides of said key lever adapted to prevent a tilting motion of the cup when the device is actuated and providing an opening in the underside of said cup whereby said character card may be rotated.

115

27. In a device of the character described, in combination, a key lever, laterally extending shoulders thereon, upwardly projecting

120

125

130

lugs, a cup having recesses adapted to receive said lugs whereby said cup is secured to said key lever, a character card within said cup, curved braces punched out from 5 the underside of said cup engaging the opposite sides of said key lever adapted to prevent a tilting motion of the cup when the device is actuated and providing an opening

in the underside of said cup whereby said character card may be rotated.

10

In testimony whereof I affix my signature, in the presence of two witnesses.

NILS H. ANDERSON.
